UNITED STATES PATENT OFFICE.

JOSEPH GEDDES, OF ROCHESTER, NEW YORK.

HEAD FOR VENTILATING OR HEATING FLUES.

1,073,978.

Specification of Letters Patent. Patented Sept. 23, 1913.

Application filed April 24, 1912. Serial No. 692,815.

To all whom it may concern:

Be it known that I, JOSEPH GEDDES, of Rochester, in the county of Monroe and State of New York, have invented a new and useful Improvement in Heads for Ventilating or Heating Flues, which improvement is fully set forth in the following specification and shown in the accompanying drawings.

10 The present invention relates to heads for ventilating or heating flues and an object of the same is to provide a construction in which the head is provided with its own closure or valve which preferably is removable to the end that the head may be used with a valved register if desired.

Another object of the invention is to provide an operating mechanism for a swinging valve, constructed to hold such valve in 20 different positions and being simple in operation and inexpensive to manufacture.

To these and other ends the invention consists in certain parts and combinations of parts, all of which will be hereinafter described, the novel features being pointed out in the appended claims.

In the drawings: Figure 1 is a front view of the head showing it in position in the wall with the valve in closed position; 30 Fig. 2 is an enlarged section on the line *a—a* of Fig. 1 showing, by full lines, the valve in closed position and, by dotted lines, in open position; Fig. 3 is an enlarged view of the operating mechanism of the valve, 35 showing the latter in open position; Fig. 4 is a vertical section of the valve operating mechanism with the valve closed; Fig. 5 is a section on the line *b—b* Fig. 3; and Fig. 6 is a perspective view of the valve operating mechanism.

In heating and ventilating systems now in use and employing flues, it is customary to provide, at the extremities of the flues, heads opening into the room or compartment to be heated or ventilated, the entrance to such heads being controlled by registers provided with valves. With such an arrangement, when the register valves are closed, an escape is provided between the register and the head as this is not a tight joint. This is disadvantageous in heating systems in that the heat escapes between the register and the head and discolors the wall in proximity to and surrounding the register. Furthermore when the valve is carried by the register, the

usual head collar, which is surrounded by the laths, becomes hot thus charring the laths so that there are possibilities of fires. This invention overcomes these defects by 60 closing the valve within the head and by causing a circulation of air within the collar when the valve is closed.

According to the illustrated embodiment, the head is formed with openings, one serving as the inlet and the other as the outlet, depending upon whether the head is used in a ventilating or in a heating system. Preferably, these openings are at right angles, the opening 1 being coextensive in area 70 with the cross sectional area of the head, while the other opening is surrounded on its exterior by a collar 2 which serves as an abutment for the laths 23 of the wall. The walls of the head may be double and 75 have their two parts spaced from each other and separated by a filler such as asbestos in board form or otherwise. The opening which surrounds the collar is not so wide nor is it so long as the head and therefore a 80 seat is provided about the said opening and within the head for engagement by a valve member 4. This valve-member is preferably in the form of a plate hinged at 5 to the end of the head opposite the opening 1, 85 so that its swinging end lies in proximity to the said opening. The valve member is substantially as wide as the interior of the head in order that, when it is thrown to the position shown in dotted lines Fig. 2, its 90 free end engages the rear wall of the head and, in this way, the valve acts as a deflector for directing air or the like from one opening in the head to the other. As the pivot is arranged within the head and in 95 proximity to the end of the casing opposite the opening 1, the full area of the opening, which is surrounded by the collar 2, is obtained.

For operating the valve 4, there may be 100 provided a slide 6 which, preferably, has two faces 7 parallel with each other but at oblique angles to the line of movement of the slide. This slide may be supported on a way 8 formed on the front face of the 105 depending bracket 9, the inclined face of the slide projecting from opposite sides of the bracket to coöperate with shoulders 10 which, in this instance, are in the form of arms extending forwardly from the valve 110 member 4 and connected to their inner ends by a piece 5 forming with the arms a U-

shaped member which projects through openings in the valve 4. The slide may be actuated in any suitable manner but, in this instance, there is employed a lever 12 pivoted at 13 and having slots 14 the walls of which coöperate with the pins 15 projecting forwardly from the slide 6. Upon the opposite side of the pivot, the lever 12 has an operating hand piece 16 by which it is manipulated. The head is so constructed that the valve and its operating parts may be removed in order that the head may be employed with any special make of register when desired. To this end, the block 17 is bolted to the inner side of the collar 2 at the end opposite the opening 1. This block is grooved on its inner face and, in its groove is arranged an anchor member 18 to which the valve 4 is pivoted at 5, said anchor member having its outer end turned laterally at 19 to coöperate with the outer face of the collar 2. Also fitted in the recess of the block 17 is a lateral extension 20 on the depending bracket 9, this extension filling up the pocket or recess and holding the anchor piece 18 against withdrawal. A spring latch 21 may coöperate with the depending bracket 9 in order to hold the extension on said bracket within the recess of the block 17. It is apparent that, when the latch is moved to free the bracket 9 and the extension 20, these parts may be withdrawn from the block 17, after which the anchoring piece 18 may drop so that the latter may be withdrawn. With this withdrawal, the valve 4 is unsupported and may be removed through the opening which is surrounded by the collar 2. A strip 22 may connect the front and rear walls of the head to prevent the dropping of the valve 4 through the opening 1 into the flue system.

When the head is installed in place, the laths 23, which are secured to the studs 24 of the building wall, project over the front wall of the head into abutment with the collar 2, as is clearly shown in Fig. 1. In the closed position of the valve, the operating mechanism is in the position shown in Fig. 1 while the open position of the valve-operating mechanism is shown in Fig. 3, the lever 16 being shifted from one extreme position to the other and, during this movement, causing the cam faces 7 to coöperate with the shoulders 10 and effecting the swinging movement of the valve 4.

A head for heating or ventilating systems constructed in accordance with this invention, is provided with its own valve which is so mounted as to give the full opening therethrough without any retarding action. The valve, when closed, acts to prevent the escape of heated air which may discolor the wall about the head and the heat is confined within the head proper where the walls are double being excluded from the

usual collar about the discharge opening so that charring of the laths does not take place. The asbestos serves as a filler between the double walls of the head and holds such walls separated while at the same time acting as a nonconductor. It also serves to prevent dust or gases from the cellar passing into the head by way of the space between the usual double walls of the flues. The valve and its operating mechanism may be removed in order that the head may be used with an ordinary register, which is otherwise unnecessary.

What I claim as my invention and desire to secure by Letters Patent is:

1. A double-walled flue-head having two openings at right angles to each other, one of said openings having an area equal to the cross sectional area of the head and the other opening having a width less than the width of the head to provide seats on opposite sides of the opening within the head, a collar surrounding the last named opening on the exterior of the head and serving as a protection for the laths of a building wall, and a valve pivoted within the head to coöperate with the seats on opposite sides of the opening, said valve having its free or swinging end located in proximity to the first named opening and adapted to coöperate with the inner face of the head, whereby the heat is confined within the double-walled head, and the collar, which protects the ends of the laths, is maintained in a cool condition when the valve is closed.

2. A double-walled flue-head having two openings at right angles to each other, one of said openings having a width less than the width of the head to provide a seat on the inside of the head about said opening, a collar projecting from the head about said opening, a valve, a member to which said valve is pivoted in such a position that the valve may coöperate with the inner wall of the head about the opening surrounded by the collar, and means for removably securing the member to the inner face of the collar, whereby the valve may be removed and the head used with a register provided with its own valve.

3. The combination with a head having an opening, and a seat surrounding said opening on the inside of the head, of a valve for coöperation with the seat, a collar surrounding said opening on the outside of the head, a block secured to the inner face of the collar and provided with a pocket, a supporting member having the valve pivoted thereto in a position to coöperate with the seat and having a retaining shoulder for coöperation with the collar, and a device inserted in the pocket of the block to hold the supporting member to the block.

4. The combination with a casing, and a pivoted valve for controlling the same, of

operating means for the valve comprising two shoulders projecting from the valve in proximity to its pivot, and a slide supported independently of the valve between the 5 projections and having cam faces at its ends coöperating with the shoulders.

5. The combination with a casing and a pivoted valve for controlling the same, of operating means for the valve comprising a 10 pair of spaced projections, and a slide having end faces arranged parallel to each other but at oblique angles to the line of movement of the said slide, said faces coöperating with the projections on the valve.

15 6. The combination with a casing provided with an opening and a collar surrounding the opening, of a valve pivoted within the casing, and operating means for the valve comprising a pair of projections 20 extending from the front face of the valve in proximity to the pivot, a guide-member depending from the collar and having a

guide thereon, and a slide movable on said guide member and having end faces arranged parallel to each other and at oblique 25 angles to the line of movement of the slide.

7. The combination with a casing provided with an opening and a collar surrounding the opening, of a valve pivoted within the casing, and operating means for 30 the valve comprising a pair of projections extending from the front face of the valve in proximity to the pivot, a guide-member depending from the collar and having a guide thereon, a slide movable on said guide 35 member and having end faces arranged parallel to each other and at oblique angles to the line of movement of the slide, and a lever pivoted to the guide member and having a pin and slot connection with the slide. 40
